[57] CLAIM

The ornamental design for doghouse, substantially as shown.

DESCRIPTION

FIG. 1 is a front elevational view of a doghouse showing my new design;

FIG. 2 is a rear elevational view thereof;

FIG. 3 is an elevational view taken from one side thereof;

FIG. 4 is an elevational view taken from the side opposite that shown in FIG. 3;

FIG. 5 is a top plan view thereof; and

FIG. 6 is a bottom plan view thereof.

Fig. 1.Fig. 2.Fig. 3.Fig. 4.Fig. 5.Fig. 6.
